UNITED STATES PATENT OFFICE.

WILLIAM S. SCALES, OF EVERETT, ASSIGNOR OF TWO-THIRDS TO JOHN B. HUMPHREY AND JOSEPH H. CLARKE, BOTH OF SOMERVILLE, MASSACHUSETTS.

DESIGN FOR A FRAME FOR RAISIN-SEEDERS.

SPECIFICATION forming part of Design No. 22,393, dated May 2, 1893.

Application filed February 6, 1893. Serial No. 461,266. Term of patent 14 years.

To all whom it may concern:

Be it known that I, WILLIAM S. SCALES, a citizen of the United States, residing at Everett, in the county of Middlesex and State of Massachusetts, have invented and produced a new and original Design for Raisin-Seeder Frames, of which the following is a specification, reference being made to the accompanying drawings, forming a part thereof.

10 Figure 1, shows a face view of my newly designed raisin seeder frame, and Fig. 2, a side view of the same.

15 The leading feature of my design consists of a cylindrical stem a , having at its upper end a circular enlargement a' , and at its lower

end a quadrangular enlargement b , having in its under face a transverse semicircular recess b' . The opposite face of said quadrangular enlargement is curved transversely to present a central raised portion b^2 . 20

I claim—

The design for a raisin seeder frame, herein shown and described.

25 In testimony whereof I have signed my name to this specification in the presence of two subscribing witnesses.

WILLIAM S. SCALES.
